UNITED STATES PATENT OFFICE.

VERNON ROYLE, OF PATERSON, NEW JERSEY.

BEVELING-MACHINE.

SPECIFICATION forming part of Letters Patent No. 598,257, dated February 1, 1898.

Application filed August 10, 1894. Serial No. 519,986. (No model.)

To all whom it may concern:

Be it known that I, VERNON ROYLE, of Paterson, in the county of Passaic and State of New Jersey, have invented a new and useful Improvement in Beveling-Machines, of which the following is a specification.

My invention relates to an improvement in beveling-machines, and more particularly to that class of bevelers which are employed in connection with half-tone plates, which leave a "proving-bearer" surrounding the beveled edge of the engraving, which bearer can be removed at will by hand or by the aid of a pair of pliers, according to the depth of the cut. In plates of this character their thinness renders them peculiarly liable to "bow up" under the cutter, and the danger of injuring the engraved surface attendant upon using ordinary forms of clamps has rendered it difficult to produce a satisfactory beveling-machine.

The object of the present invention is to provide means for overcoming the difficulties hitherto experienced and the production of a machine which shall be strong, compact, and accurate in its operations and one that may be operated with facility by unskilled as well as skilled workmen.

In the accompanying drawings, Figure 1 is a view of the machine in end or side elevation. Fig. 2 is a view in front elevation. Fig. 3 is a top plan view, the table being removed. Fig. 4 is a top plan view of the table in detail. Fig. 5 is an end view of the table, showing a portion of the carriage in section. Fig. 6 is a partial view, in front edge elevation, of the table. Fig. 7 is a top plan view of the clamp and portion of the table. Fig. 8 is a view in vertical transverse section through the clamp, its operating-shaft, and a portion of the table. Fig. 8^a is an enlarged view, in end elevation, of the mechanism for supporting and adjusting the gage, which is located on the machine-frame. Fig. 9 is an enlarged view in detail of the gage carried by the table for squaring the position of the plate. Fig. 10 is a view in face elevation of the gage-supporting plate. Fig. 11 is a view in end elevation of the gage and its supporting-plate. Fig. 12 is a partial view, in rear elevation, showing the means for adjusting the table vertically. Fig. 13 is a face view of the cutter-head with cutters in position. Fig. 14 is an edge view of the cutter-head, showing the

means for securing the cutters to the head. 55 Figs. 15 and 16 are partial plan and sectional views of one of the plates, showing the beveled grooves cut therein. Fig. 17 is a top plan view of the machine with certain of the parts broken away to show more clearly other parts beneath them; and Fig. 18 is an enlarged view in detail, showing a partial vertical section through the table along the central portion of the sliding plate G.

The pedestal on which the working parts of 65 the machine are mounted is denoted by A and is made heavy and rigid to prevent torsional strain and other derangements incidental to uneven and settling floors. It is provided with a door a, opening into its hollow interior, which latter is employed as a store-room for tools.

The table for supporting the parts to be operated upon is denoted by B' and is supported upon a carriage B, mounted upon the said pedestal. The carriage B is mounted to travel on a raised tongue or way b, fixed to the machine-frame, and on a parallel flat-faced way b', also fixed to the machine-frame. The movement of the carriage B, with its table B', 75 is intended to be sufficient to carry the plate beneath the cutter a distance equal to the length of the longest groove to be cut, and such movement is imparted to the carriage by means of a rotary shaft C, operated by a hand-wheel c and provided with a beveled gear c', which intermeshes with a bevel-gear c² on a screw-threaded shaft c³, which engages a nut c⁴, fixed to travel with the carriage. 80

The table B' is provided on its under side 90 with an elongated recess b² for the reception of the head d of an arm projecting from a rock-shaft D, journaled in the carriage, and provided with an operating-arm d', projecting from the shaft at an angle to the arm d and under the control of a thumb-screw d² to rock the shaft and thereby slide the table transversely with respect to the travel of the carriage. A spring d³ is employed to hold the arm d' against the end of the adjusting-screw 95 d², and the tension of the spring d³ is intended to be sufficient to rock the shaft D and slide the table in one direction—viz., the direction opposite that in which it is forced by the turning down of the screw d².

The table B' has an additional adjustment vertically with respect to the carriage B for the purpose of moving the work toward or

away from the cutter, and hence increasing or decreasing the depth of the beveled groove. This adjustment is effected by means of a wedge-shaped bar E, which rests and slides 5 upon a beveled seat e at the rear of the carriage, with its upper horizontal edge engaged with the rear edge of the table. The wedge-shaped bar E is held in position by means of screws e', which pass through elongated slots 10 e² in the bar and enter the rear of the carriage. The bar E is moved longitudinally with the greatest accuracy by means of a thumb-nut e³, which engages a fine screw e⁴, fixed in the end of the sliding bar E. The nut e³ is 15 held against longitudinal movement by means of a collar on its hub which loosely engages a support e⁵, fixed relatively to the bar E, so that the nut e³ may rotate freely in either direction, and hence while held against longitudinal movement itself force the screw e⁴, and hence the bar E, in one direction or the other, as may be desired.

The table B' is secured to the carriage by means of a single bolt F, which extends 25 through an enlarged opening f in the carriage and thence into the under side of the table, the bolt having inserted between its head and the carriage yielding washers f', so as to permit the swaying movement of the bolt F in the 30 carriage a distance sufficient to permit the transverse adjustment of the table with respect to the carriage and a vertical yielding movement sufficient to permit the vertical movement of the table hereinabove referred to. There is also preferably a metallic washer f² located between the head of the plate and the yielding washer or washers f' to give the bolt-head a more extended bearing on the yielding washers.

40 Lost motion due to wear between the head d of the double operating-arm and the walls of the elongated recess b², in which it engages, may be taken up by means of a sliding plate G, located in the under side of the table and 45 under the control of an adjusting-screw g to move it longitudinally and a clamping-screw g' to hold it fast to the table, the end of the plate G being located at the wall of the recess in the under side of the table, so that the recess 50 may be narrowed slightly at the point where the head d enters it.

The plate to be operated upon is clamped to the table by means of a vertically-movable clamp H, mounted at its ends in sliding adjustment in standards h, uprising from the 55 table B', and provided with a pair of rack-bars h', which mesh with pinions h² on a rotary shaft h³, mounted in said uprising standard h and operated by means of a worm i on 60 an operating-shaft I, provided with a hand-wheel i', the said worm i engaging a worm-wheel h⁴ on the shaft h³. The lower or operating face of the clamp is preferably made broad to give it an extended bearing upon the 65 plate to be held.

For placing the work in the proper position on the table B' with respect to the cutter, to

be hereinafter described, I provide two gages, one of them, K, secured to the supporting-frame and the other, L, mounted on the table. 70 The gage K is fixed in the present instance by set-screws k to a swinging frame k', pivotally secured eccentrically to the ends of a rock shaft or bar k², which latter has adjustably fixed thereon a sleeve k³, provided with 75 a collar k⁴ for turning the shaft k² and thereby throwing the gage K a greater or lesser distance over the rear edge of the plate to be operated upon. The sleeve k³, which carries the shaft k², is mounted in the upper end of 80 a supporting-standard k⁵, which standard is split at its upper end and provided with a set-screw k⁶ for the purpose of clamping the sleeve k³ in the desired rotary adjustment. During the operation of placing a plate on the 85 table to be operated upon the gage K may be utilized to align the plate with respect to the base-line which may have been utilized for purposes of etching, and after the plate has been clamped in the desired position the gage 90 K may be thrown back with its pivotal support out of the way during the operation of the cutters. To relieve the concussion when the gage K is thrown forward into operative position, I provide a spring k⁷, the free end 95 of which is in position to be engaged by a lug k⁶, fixed to rock with the swinging frame k' and so located that the said lug k⁶ will strike the spring k⁷ just before the gage reaches the limit of its forward swing. 100

The gage L is fastened by screws l to a swinging support l', fixed to the rock-shaft l², provided with an actuating-spring l³, the tension of which tends to keep the gage depressed, with its sharp edge l⁴ in the bottom of the 105 beveled groove. The gage l⁴ may be lifted from its position in the groove by means of an operating-handle l¹⁰, fixed to either the gage-supporting piece l' or to the shaft l². The rock-shaft l² is mounted in the supporting-piece l⁵, removably secured to the face of the adjustable supporting-plate l⁶, provided with a dovetailed tongue l⁷ and a tapered tongue l⁸, adapted to fit in corresponding grooves extending lengthwise of the table B'. 110 The plate l⁶ is clamped in the desired adjustment longitudinally along the table B' by means of a thumb-nut l⁹, which enters a screw secured to the dovetailed tongue l⁷, or, as I prefer, the tongue l⁷ may be the head of the 115 screw itself, the screw extending from the head or tongue l⁷ through the plate l⁶ into engagement with the nut l⁹. The gage L is used after the first groove has been cut in alignment with the gage K and serves to locate 120 the second cut exactly at right angles to the first cut for the reason that the edge of the gage L is set at right angles to the edge of the gage K, and the gage L is made to follow the vertex of the V-shaped groove first cut in locating the plate on the table for the second cut. In the same manner the third and 125 fourth cuts may be squared or located exactly at right angles to the previous cuts by em-

ploying the gage L in adjusting the plate on the table.

The cutter-head is denoted by M. It is a cylindrical-shaped disk fixed on a driving-shaft N, journaled in suitable bearings in the frame and provided with a band-pulley n for transmitting the necessary rotary movement to the cutter. The cutter-head M in the form which I have herein presented is adapted for two cutters and for this purpose is provided with grooves m and m', extending across the face of the disk, for the reception of the cutters O and O', respectively. The cutters are held in position by means of bevel-faced clamps P and P', the faces of the said clamps toward the cutter being straight, while their faces toward the opposite walls of the grooves are beveled, as shown at p and p', to correspond to the beveled walls of the grooves. The clamping-pieces P and P' are forced inwardly to clamp the cutters in position by means of set-screws Q Q', the threaded ends of which engage threaded perforations in the clamping-pieces P P'.

The plate with its grooves cut therein is denoted by R, its groove in one direction by r, and the groove at right angles thereto by r'. The particular form of the groove which I prefer to cut is of a general V shape in cross-section, with a steeper portion r² at the upper portion of the wall adjacent to the central portion of the plate. The particular form of groove is not, however, a matter of essential importance, as the cutters may be employed to simply rabbet the edge of a plate or grooves of other forms in cross-section, as may be found desirable.

What I claim is—

1. In a beveling-machine, the combination with a cutter-head and cutters carried thereby, of a carriage, means for moving the carriage bodily in its own plane, a table mounted on the carriage in position to support the plate to be operated upon, means for moving the table bodily forward and backward in a direction transverse to that in which the carriage moves and means for raising and lowering the rear edge of the carriage beneath the cutters while the opposite edge retains its position upon the carriage, substantially as set forth.

2. In a beveling-machine, the combination with the cutter-head and cutters, of a carriage, a table mounted on the carriage in position to support the plate to be operated upon, a tapered adjusting bar or plate located between the carriage and that portion of the table beneath the cutters, an adjusting device for advancing and withdrawing the tapered adjusting bar or plate for raising or lowering the rear edge of the table beneath the cutters, while the opposite edge retains its position upon the carriage and means for moving the table bodily forward and backward transversely to the movement of the carriage and independently of the said adjusting device, substantially as set forth.

3. The combination with the cutter-head and cutters, of a table for supporting the plate to be operated upon, means for advancing the table, along the path of the cutters, an angle-lever having one of its arms engaged with the table and an adjusting device engaged with the opposite arm of the angle-lever for moving the table transversely to its movement along the path of the cutters, substantially as set forth. 70

4. The combination with the cutter-head and cutters, of a carriage mounted to travel along in proximity to the cutters a table mounted on the carriage in position to support the plate to be operated upon, a screw 80 feed under the control of the operator to advance the carriage and the table supported thereon and a table-adjusting device mounted on the carriage for moving the table transversely to the movement of the carriage, substantially as set forth. 85

5. The combination with the cutters, the table for supporting the plate to be operated upon and means for operating the table, of a swinging gage mounted on a support fixed relatively to the table and an eccentric connecting the gage with its support for adjusting the gage at different distances over the 90 edge of the table, substantially as set forth. 95

6. The combination with the cutters, the table for supporting the plate to be operated upon and means for operating the table, of a swinging gage mounted on a support fixed 100 relatively to the table, an eccentric connecting the gage with its support for adjusting the gage at different distances over the edge of the table and means for cushioning the fall of the gage, substantially as set forth. 105

7. The combination with the cutters, the table for supporting the work to be operated upon and means for operating the table, of means for indicating the base-line for the first 110 cut and a pivoted gage secured to the table in sliding adjustment for indicating a cut at right angles to the base-line, substantially as set forth.

8. The combination with the table for supporting the plate to be operated upon and provided with a groove along its surface, of a gage-supporting plate provided with a tongue to fit the groove, means for holding the plate in its adjustment along the table and a gage pivoted to the said supporting-plate with its 115 edge transverse to the sliding movement of the support, substantially as set forth. 120

9. The combination with a table for supporting the plate to be operated upon and provided with means for securing a gage thereto, of a gage consisting of a straight-edge and means for swinging the straight-edge toward and away from the table and for sliding it along the table, substantially as set forth. 125
